UNITED STATES PATENT OFFICE.

WILLIAM E. LALLEY, OF REPUBLIC, WASHINGTON.

CAR-REPLACING DEVICE.

1,162,867.

Specification of Letters Patent.

Patented Dec. 7, 1915.

Application filed July 7, 1914. Serial No. 849,502.

To all whom it may concern:

Be it known that I, WILLIAM E. LALLEY, a citizen of the United States, residing at Republic, in the county of Ferry, State of Washington, have invented certain new and useful Improvements in Car-Replacing Devices; and I do hereby declare the following to be a full, clear, and exact description of the invention, such as will enable others skilled in the art to which it appertains to make and use the same.

This invention relates to certain novel and useful improvements in a device for replacing cars upon the rails of the track.

In carrying out my invention it is my purpose to provide car replacing devices which are reversible in the sense that they may be employed for placing cars upon the tracks in either direction, and furthermore, the device may be placed against the inner sides or outer sides of the rails as the occasion may demand.

Still a further object of my invention is the provision of car replacing devices which will embody in their construction the desired features of simplicity, efficiency, reliability and convenience, and by means of which devices a car may be quickly and readily replaced upon the track after it has been derailed.

With the above recited objects and others of a similar nature in view, my invention consists in the construction, combination and arrangement of parts set forth in and falling within the scope of the appended claim.

In the accompanying drawings: Figure 1 is a top plan view of a section of a track way and showing my invention applied thereto. Fig. 2 is a cross sectional view 40 taken on the line 2-2 of Fig. 1. Fig. 3 is a perspective view of one of the car replacing frogs. Fig. 4 is a similar view of the other car replacing frog.

In the practice of my invention I employ a pair of frog members, one of which is adapted to be placed upon the ties in such manner as to abut against the inside face of one rail, while the other member is so positioned as to abut against the opposite side 50 of the outside rail, this latter member having a portion overlying the tread section of the rail. Furthermore, the frog members are so constructed that they may be employed for replacing cars in either direction upon the track way.

Referring now to the accompanying drawings in detail, the ties of the track are shown at 1, while the usual track rails are indicated at 2.

My invention embraces a pair of wrecking or replacing blocks for replacing the cars upon the track, one member of the pair of blocks being indicated as an entirety by the letter A, while the other member is similarly indicated by the letter B.

The frog member A is adapted when in use to rest upon the ties and have one of its side edges abut against the inner face of the track rail. This member A comprises a metallic body having a flat substantially rectangular base 3 which is adapted to bear upon the ties, the top of this frog member being then curved or swelled upward from the transverse edge 4 toward the opposite transverse edge 5. The top of the frog member A is further formed with inwardly beveled grooves 6, which extend substantially parallel with each other as at 7-7, these grooves then diverging relatively to each other as shown at 8-8, the result being that an elevated web or barrier 9 is formed between the diverging portions 8-8 of the grooves.

The frog member A is further provided with a tongue 10 which is adapted to be slipped beneath the rail between the ties and has an upwardly turned terminal 11 forming a hook so that the frog member may be fastened or secured to the rail and held against dislodgment. This tongue is pivoted, as at 12, to the base of the frog, and this base may, if desired, be roughened or corrugated, as at 13, and provided with small tie engaging spurs 14.

The other member B is formed of a metallic plate having a flat base 15 which is roughened or corrugated, as at 16, to grip the ties, and is provided with small tie engaging spurs 17. This base is provided with sides 19-19 which taper or diverge toward each other from the end 20, the plate then spreading or flaring to form a head 21, having the rounded top 22. This head is of relatively less thickness than the body of the plate and its under face is flattened, as at 23, to rest upon the tread of the rail, as shown in Fig. 1, the opposite sides of the head being provided with downwardly extending rail gripping lugs 24. The tongue 25 is pivoted, as at 26, to the for-

ward end of the plate section of the frog and beneath the head, and is provided at its outer or free end with a downwardly turned lug 27 adapted to rest upon the tie or ground and form a support for the outer portion of the head of the frog. The top of the frog is swelled or curved and is formed with diverging grooves 29—29, these grooves approaching each other at their center portions and diverging at their ends, as clearly shown in Fig. 1, a swelled or curved web 30 being formed between the two grooves.

From the above description, taken in connection with the accompanying drawings, the construction and manner of employing these frogs for replacing a car will be readily apparent. The frog A in position is shown in Fig. 1 with one of its side faces flush with the inner side of the rail and is fastened to the rail by means of the hook before mentioned. The other frog member B is placed against the outside of the opposite rail with the head portion of this frog partially overlying and resting upon the tread portion of the rail, one of the side lugs of the head holding the latter to the rail, while the small pivoted arm or tongue having the depending lug assists in supporting and staying the outer portion of the head away from the rail.

Assuming a car to be derailed, the wheels of the car, which are conventionally illustrated at W—W, are pinched or pushed forward until the flanges of the wheels ride upon the frogs in the grooves thereof which are nearest the rails, and then directed or guided by the webs and grooves of the frogs, the wheels retaking the track in the manner readily understood in devices of this class.

It will be noted that these frogs are so constructed that they will not slip when placed in position, and furthermore, are ex-

ceedingly simple in construction and may be readily manipulated and placed in position for returning the derailed car to the track.

What I claim is:

A car replacer including a frog member adapted to be placed against the inside of the track, said frog having a substantially rectangular base portion adapted to rest upon the ties, a tongue bolted to and extending from the base portion and adapted to fit beneath the rails, said tongue terminating in an upturned hook adapted to engage the adjacent edge of the rail, the upper portion of the frog being curved or swelled toward the opposite end and provided with grooves which diverge relatively to each other from one end portion toward the opposite end portion, said grooves being adapted to receive the flanges of the car wheel, and a second frog member adapted to fit against the outside of the opposite track rail, said second frog member comprising a plate section having a swelled or curved upper portion terminating at one end in an enlarged head adapted to partially overlie and rest upon the track rail, said second member having a pair of grooves therein which converge toward their middle portions and diverge toward their end portions, said grooves being adapted to receive the flanges of the car wheels, and a laterally extending tongue projecting outward from the second block member and having a downturned end adapted to rest upon the adjacent ground surface to support the tongue in position relative to the rail.

In testimony whereof, I affix my signature, in the presence of two witnesses.

WILLIAM E. LALLEY.
